UNITED STATES PATENT OFFICE.

PAUL EARNEST NELSON, OF RED WING, MINNESOTA.

BLEACHING LIQUID AND PROCESS OF MANUFACTURING SAME.

1,414,039.

Specification of Letters Patent. Patented Apr. 25, 1922.

No Drawing.

Application filed May 3, 1921. Serial No. 466,602.

To all whom it may concern:

Be it known that I, PAUL E. NELSON, a citizen of the United States, and a resident of Red Wing, in the county of Goodhue and 5 State of Minnesota, have invented certain new and useful Improvements in Bleaching Liquids and Processes of Manufacturing Same, of which the following is a specification.

10 This invention relates to improvements in bleaching liquids, and a process of manufacturing the same, and the object of the invention is to provide a simple process or method of producing the liquid, which liquid may 15 be used almost with impunity in connection with the most delicate linen, which is very mild, has good bleaching and water softening qualities, may be used by the housewife or laundress in doing the wash at home with 20 an electric or other washing machine or the like, or in fact in any other way, without injury to the most delicate cloth or linen and which bleaching liquid though mild will also remove nearly all stains including ink and 25 iodine without injury, to the fabric.

Bleaching liquid is generally or usually produced by mixing or combining caustic lime, soda, carbonate or pure sodium carbonate with some substance containing and 30 adapted to free chlorine, so that the latter is absorbed with said caustic lime or soda, together with water, as represented by the following formulas:

or,

or

45 In producing "Javelle water," bleaching powder or chloride of lime is treated with potassium carbonate, but generally results in improper bleaching qualities and is not sufficiently mild to permit use thereof at 50 home by the housewife or laundress, in the usual process of washing machine or the like without serious injury to fabrics. The reaction is represented as follows:

55 In accordance with the present invention, the bleach is made of one or both of the following limes, namely, chloride of lime or chlorinated lime, this chloride carry-

ing chlorine gases and being combined with sodium carbonate, in lieu of caustic soda or pure sodium carbonate. To produce 30 gallons or rather 28 gallons allowing two gallons for settling, the following formula is used and it has been found to be very economical and to produce a very mild and desirable bleach:

In a 30 gallon jar is placed or poured two 65 gallons of cold water, to which five pounds of chloride of lime or chlorinated lime is added, the mixture being stirred until well dissolved. Then add 10 pounds of washing soda, or sodium carbonate and mix well, subsequently adding hot water until the solution in the jar is warm, after which the jar is filled with cold water and allowed to set until the mixture is settled. The solution thus produced is a very good and efficient bleach and 70 so mild it can be used by the housewife where the washing is done at home either in an electric washing machine or the like, or in any other way without possible injury to the most delicate linen. Furthermore, although 75 it is mild it removes nearly all stains from clothes without injury to the fabric.

In the addition of two or three gallons of cold water to five pounds of chloride of lime, after which the same is thoroughly stirred to 85 dissolve the lime, a thick paste is produced by the addition of the washing soda, so that all lumps are dissolved and avoided by bringing the hot water into the solution, the temperature is raised to about from 170 to 90 180° and when the temperature rises the solution becomes pink due to impurities in which condition it is an effective soft bleach and serves as a water softener. It has been found in practice that if the temperature is 95 not brought up to over 120°, it may break and turn green and will not act as a water softener or bleach which is useless, a hard bleach being thus produced. By the time the hot water is added to bring the temperature 100 up to 180°, the jar is about one-half full so as to contain about 15 gallons and the chlorine gases are escaping. To prevent this loss and retard the decomposition of the hypochlorous acid and the chlorine gas of a nascent character which is given off and which would otherwise escape, the jar is filled with cold water, thereby lowering the temperature 105 to about 70°.

Also by raising the temperature, dissolving of the chloride of lime or chlorinated lime and washing soda is facilitated, thereby 110

securing more strength from both ingredients. In using the bleach, the housewife will have a chemical which will be of great assistance as it is not only a practical bleach, but will remove fruit stains and many other stains from all cotton goods while at the same time being so mild as to prevent injury to the fabric, as well as softening the water. This is due to the fact that the washing soda is a water softener. The bleach is adapted to be used in the suds or soapy water in the tub or washing machine, and will not injure cotton or linen fabrics of a delicate character. It will also take out colors that have run from one goods to another and is a positive bleacher of cotton and linen goods.

In addition, a further step may be employed in that after making up the bleach there is added thereto a small quantity, preferably about 4 oz. of sodium bisulphite and a small quantity, preferably about 4 oz. of acetic acid which is stirred thoroughly into the bleaching liquor or mixture. By adding these two chemicals, it is possible to take out or remove ink and iodine stains or the like from fabrics without changing the water softening qualities of the product as before produced. It will also assist in the removal of fruit stains.

30 In view of the foregoing, it will be apparent that I have provided a very simple, cheap and economical form of process and bleaching liquor produced therefrom which will effectively serve the purposes intended.

35 Having thus described my invention what I claim is:—

1. A bleaching liquid containing chloride of lime, sodium carbonate, sodium bisulphite and sodium acetate.
- 40 2. A bleaching liquid comprising a bleach, sodium carbonate and sodium bisulphite.
3. A bleaching liquid comprising a bleach, sodium carbonate, sodium bisulphite and sodium acetate.
- 45 4. A bleaching liquid containing water, chloride of lime, sodium salts and sodium acetate.
- 50 5. A process of producing a bleaching liquid consisting in adding to a quantity of cold water, a quantity of chloride of lime, stirring the mixture, adding a quantity of sodium carbonate, mixing the same and adding hot water to raise the temperature, allowing the same to stand after thoroughly dissolving the chloride of lime and sodium carbonate and then cooling the same.
- 55 6. A process of producing a bleaching

liquid consisting in adding to a quantity of cold water, a quantity of chloride of lime adapted to give off chlorine gases, stirring the mixture, adding a quantity of sodium carbonate, mixing the same and adding hot water to raise the temperature, allowing the same to stand after thoroughly dissolving the chloride of lime and sodium carbonate and then cooling the same, and then adding small quantities of sodium bisulphite and acetic acid.

7. A process of producing a bleaching liquid consisting in combining the ingredients in substantially the proportions as follows: adding about five pounds of chloride of lime to about two or three gallons of cold water, stirring the same to dissolve the chloride of lime, adding about ten pounds of sodium carbonate, and mixing the same into a paste so as to dissolve in such relatively small amounts of cold water the lumps of chloride of lime, adding hot water to raise the temperature to about from 150 to 180° and above 120° until the solution becomes caked and is thereby prevented from turning green and breaking to produce a softener for water or soft bleach, and then adding the remaining quantity of cold water to lower the temperature to about 70°, thereby avoiding the escape of the chlorine gases by preventing loss and decomposition of the volatile acid.

8. A process of preparing a bleaching liquid consisting of adding to water, a quantity of chloride of lime, a quantity of sodium carbonate, sodium bisulphite and acetic acid.

9. A process of producing a bleaching liquid consisting in combining the ingredients in substantially the following proportions and manner: taking two gallons of cold water and adding thereto five pounds of chloride of lime stirring said mixture until the chloride of lime is thoroughly dissolved, adding ten pounds of sodium carbonate and stirring to form a paste, dissolving the paste in hot water, enough hot water being added to raise the temperature until the solution turns pink, adding cold water to make the solution up to ten gallons and lowering the temperature to 70° F. to avoid the escape of chlorine gas and retard the decomposition of the volatile acid, then adding four ounces of sodium bisulphite and four ounces of acetic acid.

PAUL EARNEST NELSON.
